UNITED STATES PATENT OFFICE.

PER OLOF OLSSON, OF MARSHALL, MINNESOTA.

DESIGN FOR A ROPE-CLAMP FRAME.

SPECIFICATION forming part of Design No. 23,870, dated December 11, 1894.

Application filed March 17, 1894. Serial No. 504,098. Term of patent 8½ years.

To all whom it may concern:

Be it known that I, PER OLOF OLSSON, a citizen of the United States, residing at Marshall, in the county of Lyon and State of Minnesota, have invented and produced a new and original Design for a Rope-Clamp Frame, of which the following is a specification, reference being had to the accompanying drawing, forming part thereof, in which the figure represents a perspective view of a rope-clamp frame embodying my new design.

The leading feature of my design consists in the edge contour of the frame presenting a series of alternate convexities and concavities.

The plate of the base b , is essentially a plane surface, and disposed thereon is a rib-like figure b' , which is crossed near one end by a short transverse angular figure c , that ranges parallel with the plane of the surface of the base b . The marginal line of the base

is irregular and is made up mainly of alternate concavities and convexities. Thus the convexity b^2 is produced about opposite the figure b' and at the left of the convexity b^2 are the convexities b^3 b^4 , separated by a concavity b^5 , and at the right is the convexity b^6 separated from the convexity b^2 by a concavity b^7 , the curve of which is more sweeping than that of the concavity b^5 at the opposite side edge of the base. The remaining bottom edge of the base is also irregular, and presents a single projecting figure b^8 , of which the side lines are concavo-convex, while the outer edge or side b^9 , is straight.
